UNITED STATES PATENT OFFICE

NATHAN P. BLOOM, OF LOUISVILLE, KENTUCKY, ASSIGNOR TO ADLER MANUFACTURING CO., OF LOUISVILLE, KENTUCKY, A CORPORATION OF KENTUCKY

DESIGN FOR A CABINET FOR A SOUND-REPRODUCING INSTRUMENT OR THE LIKE

Application filed July 5, 1929. Serial No. 31,941. Term of patent 3½ years.

To all whom it may concern:

Be it known that I, NATHAN P. BLOOM, a citizen of the United States, residing at Louisville, in the county of Jefferson and State of Kentucky, have invented a new, original, and ornamental Design for a Cabinet for a Sound-Reproducing Instrument or the like, of which the following is a specification, reference being had to the accompanying drawing, forming a part hereof.

The drawing is a perspective view of the cabinet embodying my new design.

I claim:

The ornamental design for a cabinet for a sound reproducing instrument or the like as shown.

NATHAN P. BLOOM.
